UNITED STATES PATENT OFFICE.

RONALD B. JESTER, OF NEW CUMBERLAND, WEST VIRGINIA.

LIFTING-JACK.

1,304,569.

Specification of Letters Patent.

Patented May 27, 1919.

Application filed May 22, 1918. Serial No. 235,917.

To all whom it may concern:

Be it known that I, RONALD B. JESTER, a citizen of the United States, and resident of New Cumberland, in the county of Hancock 5 and State of West Virginia, have invented a new and useful Improvement in Lifting-Jacks, (Case 2;) and I do hereby declare the following to be a full, clear, and exact description thereof.

10 My invention relates to lifting-jacks, and more especially to the type of jack illustrated and described in an application filed by me January 11, 1918, Serial No. 211,331, in which the lifting-bar has oppositely-disposed teeth and a lifting-pawl working between said teeth, said lifting-pawl being raised and lowered, and when in engagement with the teeth on one side, the lifting of the bar is accomplished, and when the lifting- 15 bar has reached the limit of its upward movement, the lifting-pawl is shifted automatically to the opposite set of teeth and the lifting-bar lowered step by step.

20 The object of the present invention is to provide a new form of mechanism for shifting the lifting and lowering pawl, which has some advantage over the construction of said application, and the invention comprises the novel features hereinafter set forth and claimed.

25 In the accompanying drawing, Figure 1 is a side view of my jack; Fig. 2 is a vertical section; Fig. 3 is a section on the line 3—3, Fig. 2; Fig. 4 shows the position of 30 the lifting and lowering-pawl with the lifting-bar at the upper limit of its stroke and in position for shifting; Fig. 5 shows the lifting and lowering-pawl after it has been shifted to reversing positions; Fig. 6 is a detail showing the position of the holding pawl in the lowering operation; Fig. 7 is a view of the holding pawl in position for shifting the lifting and lowering pawl back to raising position; and Fig. 8 is a perspective view of the holding-pawl.

40 In the drawing, the numeral 2 designates a suitable frame or casing for containing the parts, supported on a base 3. Fitting within the casing 2 is the lifting-bar 4, which is adapted to move up and down with the said casing as a guide, and said bar has the recessed portion 5 with the oppositely-disposed teeth 6 and 7. In the rear of the bar are the teeth 8.

45 Journaled in bearings 9 and 10 in the frame is the shaft 11. The bearings 9 and

10 are arranged at an angle, as illustrated in Fig. 3, for convenience in operation, and the outer end of the shaft 11 has the wrench-seat 12 for the attachment of a wrench to 60 impart a rotary movement to said shaft. The inner end of said shaft has ball-bearings to relieve the thrust-friction. It will be apparent that by having the shaft arranged at an angle the operator does not 65 have to stoop so low, and there is less chance for interference with the ground in the turning of said shaft.

70 The shaft 11 is provided with the crank 13, and said crank engages the lower end of the lifting and lowering-pawl 14, so that by the rotation of the shaft 11 an upward and downward movement is imparted to said lifting and lowering-pawl. The lower end of said pawl is bent as at 15 to conform to 75 the angular position of the shaft 11, while the upper portion of said pawl is parallel to the walls of the frame 2. At the upper end of the pawl 14 is the lug or enlargement 16, which is triangular in form, and 80 within said lug is the seat 17 to receive the pin 18, a spring 19 being interposed between a plug and the head 20 of said pin whereby said pin is adapted to yield under certain 85 conditions.

85 A holding-pawl 21 is provided which is pivotally-mounted on the frame at 22, said pawl having the teeth 23, which engage the teeth 8 on the rear of the lifting-bar, and said teeth are held normally in engagement 90 with said teeth on the lifting-bar by the spring 25. The holding-pawl 21 has the face 26, which is engaged by the pin 18 in the raising of the lifting-bar, and a cam-face 27, which is engaged by the pin during the lowering operation of the lifting-bar, and a shoulder 21^a,—preferably a continuation of the cam-face 27,—adapted to be engaged by the pin 17 for tripping the pawl, all as fully hereinafter set forth.

100 The lower end of the lifting-bar 4 has the cam-lug 28, which acts to shift the pawl by its engagement with the lug 16 on said pawl, as fully hereinafter set forth.

105 A spring 29 is secured to the inside of the frame 2 and said spring bears against one side of the lifting and lowering-pawl 14, and said spring acts to shift said pawl when the lifting-bar has been lowered to bring said pawl into position for again raising the 110 lifting-bar.

At the upper end of the lifting-bar on the

rear face just above the toothed portion 8 is the recess 30 of less depth than the teeth 8, and with which the pawl teeth 23 engage when the lifting-bar has reached its lower 5 limit of movement.

In the operation of my improved jack, with the pawl 14 in the position indicated in Fig. 2, a suitable crank is applied to the seat 12 of the shaft 11, and a rotary movement imparted to said shaft. This will act to alternately raise and lower the pawl 14, and the lug 16 at the upper end of said pawl engaging the teeth 6 on the right-hand side of the lifting-bar will raise the lifting-bar by step by step motion, the holding-pawl 21 moving in and out by the action of the spring 25 so as to hold the lifting-bar in its raised position while the pawl 14 is being lowered to engage another tooth. The 10 lifting-bar is lifted in this manner until the cam-lug 28 at the lower end of said bar engages the triangular-shaped lug 16 of the pawl 14, whereupon said pawl is shifted to the left to engage the teeth 7. In this movement of the pawl 14, the pin 18 moves diagonally from its position on the face 26 until it passes over the raised portion 32 and is forced by the spring 19 into position for engagement with the cam-face 27 of the 15 holding-pawl 21.

By the continued rotation of the shaft 11 in the same direction, the lowering of the lifting-bar now takes place; the pin moving along the cam face 27 on the upstroke of the pawl directs the pawl to engage with the teeth 7, as indicated in Fig. 5. Upward movement of the pawl carries the pin into engagement with the shoulder 21^a of the holding-pawl 21, tripping said pawl, as 20 clearly shown in Fig. 6. This tripping of the holding-pawl takes place substantially at completion of the upstroke, the pin 18 acting to hold said pawl out of engagement with the holding ratchets until the lifting-bar has 25 lowered sufficiently to allow for the engagement of the pawl with the next higher ratchet.

In this way by step by step movement, the lifting-bar is lowered, and finally with the 30 pawl-teeth 23 engage the recess 30 in the lifting-bar, and as said recess is of less depth than the teeth 8, the pawl 21 is held from moving into its normal position, as indicated in Fig. 7. When the pawl 14 is lowered 35 with the holding-pawl 21 in this position, the pin 17 will then pass below the cam-face 27, as indicated in Fig. 7, whereupon the spring 29 forces the pawl 14 over again into engagement with the teeth 6 in position for 40 again raising the lifting-bar.

What I claim is:

1. In a lifting-jack, the combination with a suitable frame, of a lifting-bar having oppositely-disposed teeth, a holding-pawl, 45 teeth on said lifting-bar engaged by said

holding-pawl, a lifting and lowering-pawl arranged between said oppositely-disposed teeth, means carried by said frame for raising and lowering said last-named pawl, means carried by said lifting-bar adapted to move said last-named pawl from one set of teeth to the other, a yielding-pin carried by said last-named pawl, a cam-face on said holding-pawl adapted to be engaged by said pin, and means for tripping said holding- 70 pawl by the movement of said pin. 75

2. In a lifting-jack, the combination with a suitable frame, of a lifting-bar having oppositely-disposed teeth, a holding-pawl, teeth on said lifting-bar engaged by said holding-pawl, a lifting and lowering pawl arranged between said oppositely disposed teeth, means carried by said frame for raising and lowering said last-named pawl, a triangular-shaped lug at the upper end of 80 said last-named pawl, a cam-lug on said lifting-bar adapted to engage said lug on said lifting and lowering-pawl, a yielding pin mounted in said last-named pawl, a cam-face on said holding-pawl adapted to be engaged by said pin, and means for tripping said holding-pawl by the movement of said pin. 85

3. In a lifting-jack, the combination with a suitable frame, of a lifting-bar having oppositely-disposed teeth, a spring-actuated holding-pawl, teeth on said lifting-bar engaged by said holding-pawl, a lifting and lowering-pawl arranged between said oppositely-disposed teeth, means carried by said lifting-bar for shifting said last-named pawl from one set of teeth to the other, means carried by said frame for raising and lowering said last-named pawl, a yielding-pin mounted in said last-named pawl movable in engagement with a plain face of said holding-pawl during the lifting of the lifting-bar, a cam-face on said holding-pawl engaged by said pin during the lowering of said lifting-bar and means for tripping said holding-pawl by the movement of said pin. 95 100 105

4. In a lifting-jack, the combination with a suitable frame, of a lifting-bar having oppositely-disposed teeth, a spring-actuated holding-pawl, teeth on said lifting-bar engaged by said holding-pawl, a notch formed in said lifting-bar above said last-named teeth of less depth than said last-named teeth, a lifting and lowering-pawl arranged between said oppositely-disposed teeth, means carried by said frame for raising and lowering said last-named pawl, means carried by the lifting-bar for shifting said last-named pawl from one set of teeth to the other, a yielding-pin carried by said last-named 115 120 125 pawl, a cam-face on said holding-pawl adapted to be engaged by said pin, and a spring bearing against said lifting and lowering-pawl.

5. In a lifting-jack, the combination with 130

- a suitable frame, of a lifting-bar having oppositely-disposed teeth, a spring-actuated holding-pawl, means for holding said holding-pawl out of engagement with said teeth 5 when the lifting-bar has been completely lowered, a lifting and lowering-pawl arranged between said oppositely-disposed teeth, means carried by said frame for raising and lowering said last-named pawl, and 10 means for shifting said last-named pawl from one set of teeth to the other.
6. In a lifting-jack, the combination with a suitable frame, of a lifting-bar having oppositely-disposed teeth, a spring-actuated holding-pawl, teeth on said lifting-bar engaged by said holding-pawl, a lifting and lowering-pawl arranged between said oppositely-disposed teeth, means carried by said lifting-bar for shifting said last-named pawl 15 from one set of teeth to the other, means carried by said frame for raising and lowering said last-named pawl, a yielding pin mount- 20
- ed in said last-named pawl, a cam-face on said holding-pawl engaged by said pin during the lowering of said lifting-bar, and a 25 projection on said holding-pawl engaged by said pin whereby said holding-pawl is moved out of engagement with the teeth on said lifting-bar.
7. In a lifting jack, the combination with 30 a suitable frame, of a lifting bar having teeth, a holding pawl, a lifting and lowering pawl, a rotary shaft in said frame inclined downwardly from its operating end, and connections between said shaft and said lifting and lowering pawl for operating the same.
- 35 In testimony whereof, I, the said RONALD B. JESTER, have hereunto set my hand.

RONALD B. JESTER.
